COMBINED ROTISSERIE OVEN AND FOOD WARMING DISPLAY COUNTER

Charles M. Vaughan, 28 Frontus St., Greenville, S.C.

Filed Feb. 14, 1962, Ser. No. 68,821

Term of patent 14 years

(Cl. D81—10)

Fig. 1.

Fig. 2.

Fig. 3.

FIGURE 1 is a perspective view of a combined rotisserie oven and food warming display counter embodying my new design, and

FIGURE 2 is a perspective view taken from the rear of FIGURE 1 of the combined rotisserie oven and food warming display counter illustrated in FIGURE 1.

FIGURE 3 is an elevational view taken from the left of FIGURE 1.

I claim:

The ornamental design for a combined rotisserie oven and food warming display counter, substantially as shown.
